UNITED STATES PATENT OFFICE.

ARTHUR C. HELM, OF McCOOK, NEBRASKA.

WELL CASING.

Application filed March 6, 1924. Serial No. 697,388.

This invention relates to well casings and has for its object to generally improve upon such structures so as to provide a device of this nature having a sturdy, durable, and 5 light structure which may be easily assembled and which will be efficient in use.

Another important object of the invention is to provide sections of a well casing having associated therewith novel straining 10 means.

A still further object of the invention is to provide a well casing including a plurality of superimposed sections one of which is adapted to be disposed in water and embodies a filter through which the water must 15 pass to flow into the casing.

With the above and numerous other objects in view as will appear as the description progresses, the invention resides in certain 20 novel features of construction, and in the combination and arrangement of parts as will be hereinafter more fully described and claimed.

In the drawing:

25 Figure 1 is an elevation of the well casing embodying my invention, portions thereof being shown in section.

Figure 2 is a detail longitudinal section through the intermediate portion D of the 30 casing,

Figure 3 is a transverse section taken substantially on the line 3—3 of Figure 2 looking in the direction of the arrow,

Figure 4 is an elevation showing portions 35 of the sections,

Figure 5 is a detail transverse section taken substantially on the line 5—5 of Figure 4 looking in the direction of the arrows,

Figure 6 is a transverse section taken on 40 the line 6—6 of Figure 4 looking in the direction of the arrows,

Figure 7 is a perspective view of the filter block,

Figure 8 is a perspective view of the housing for the filter block,

Figure 9 is a longitudinal section through a modified form of the casing,

Figure 10 is a transverse section therethrough taken substantially on the line 50 10—10 of Figure 9 looking in the direction of the arrows, and

Figure 11 is a detail perspective showing a portion of the modified form of the casing.

Referring to the drawing in detail it will be seen that A designates the outer casing

which is extended down as far as water level B. The inner casing is spaced from the outer casing and is formed from a plurality of sections. The bottom section C is disposed below the water. The section D is disposed above section C in superimposed relation thereto so as to be positioned in the water. A section E is mounted on top of section D and a beveled section F is mounted 60 thereon. This beveled section F is connected to a pipe G of suitable length. The space above the section E is filled with gravel as is shown at H and concrete is poured on top of the gravel to fill the remaining space 70 between the inner casing and the outer casing as is indicated at J. The sections of the inner casing are all joined together in the same manner preferably by the engagement of threaded extensions 5. Section 75 C merely acts as a hollow reservoir and also as a foundation or anchor for the casing. Section D acts as a filter and embodies a novel structure including the inner cylindrical member 10 radiating from 80 which are the two series of tubes 11, one series being disposed adjacent the upper end and the other series disposed adjacent the lower end. Corresponding tubs 11 of the two series connect with housings 12 in which are 85 supported filter blocks 13 having a plurality of slots 14 therein preferably extending transversely thereof. These slots are larger toward the inner face of the block 13 as is indicated to advantage in Figure 2. A band 90 15 is suitably fixed to the collar 16 of a conical shaped member 17 the smaller end of which terminates in a collar 18 fixed to the inner cylindrical member 10. A pair of tubes 19 are fastened to the band 15 and depend therefrom so as to be fastened to a lower band 20 upon which the housings 12 95 rest. As is shown to advantage in Figures 4 and 8 tabs 22 are provided at the tops and bottoms of the housings 12 and are fixed to the bands 16 and 20. The filter blocks 13 are held within the housing 12 by means of lips 23 at the tops and bottoms thereof which are bent over upon the blocks as is shown to advantage in Figure 2. The housings are 100 provided with side strips 24 which meet each other as is seen in Figure 3 and it is preferable to fill the space between the housings and the inner cylindrical member 10 with concrete or similar material.

110 The section E is similar in construction to sections C consisting merely of an outer

cylinder 26 and an inner cylinder 27 the upper end of the outer cylinder converges and connects with the inner cylinder. Section F is similar in construction to section E except that the outer cylinder is tapered. The outer cylinder 26 of the section E forms a protective casing to shield the inner conducting cylinder 27 from the pressure of the packed gravel H which is filled about 10 this section. The outer tapered cylinder mounted upon the section F tends to divert the gravel as it is being poured in the outer casing and likewise protects the lower end of the section F from the pressure of the 15 gravel.

The modification of the invention shown in Figures 9, 10 and 11 shows a plurality of sections held together by means of cables 30 which will be attached to the end sections 20 by rivets 31 or in any other suitable manner. Each section shown in this modification consists of an outer cylinder 32 and an inner cylinder 33. The inner cylinder is longer than the outer cylinder and the exposed end is provided with a plurality of radiating fins or plates 34 which are connected to the outer cylinder. The space between the cylinders is filled with gravel or the like. From this construction it is obvious that a portion of the inner cylinder 33 30 is exposed so that the water may be received in the inner cylinder through the openings.

The sections embodied in this modification are preferably to be employed upon 35 wells of comparatively large diameter and used in place of the upper sections shown in Figure 1 indicated by the letters F and G, above the water line and gravel filling, above the sections C, D and E which may 40 remain of the type shown in the preferred form in this figure.

I have, in the present instance, shown and described the preferred embodiment of my 45 invention which will give in practice satisfactory and reliable results, and it is to be understood that the same are susceptible of modifications in various particulars such as the details of construction, and the combination and arrangement of parts, without 50 departing from the spirit or scope of the invention as hereinafter claimed or sacrificing any of its advantages.

It is evident that this well casing is

adapted to be used with a large variety of pumps and as such devices are well known 55 in the art I have not shown any in the accompanying drawing. The device is particularly adapted for use in water wells, but, of course, may be useful in other wells and I do not wish to limit myself to the particular illustration and the use mentioned herein.

Having thus described my invention, what I claim as new is:

1. A well casing section including a cylindrical core, a conical shaped member connected to the core, a band fixed to the conical shaped member, a second band, tubes connecting the two bands, a plurality of housings mounted between the bands, filtering 70 blocks disposed within the housings, and means connecting the housings with the core.

2. A well casing of the class described comprising a bottom section forming a reservoir, a filter section arranged in vertically aligned position with the reservoir section having a plurality of openings formed in the side walls communicating with the interior thereof, the said section being 80 of assembled formation to permit replacement of the parts, a conducting section disposed above the filter section and communicating therewith provided with an outer cylindrical casing assembled to provide a 85 unitary structure, and a plurality of conducting sections communicating with and disposed above the said last mentioned section.

3. In a well casing comprising a plurality of superimposed sections adapted to conduct well water and the like therethrough, an intermediate filler section comprising a plurality of housings, a pair of bands connected to the upper and lower ends 95 of the housings, perforated filter blocks mounted in the housings, a cylindrical conducting member extending longitudinally through the center of the section, and a series of radially directed tubes connected to 100 the conducting tube and to the housings and communicating therewith so as to conduct the water through the blocks to the central conducting tube.

In testimony whereof I affix my signature.
ARTHUR C. HELM.
